UNITED STATES PATENT OFFICE

MEYER BENJAMIN CHERNIAK, OF NEW YORK, N. Y.

DESIGN FOR A LIGHTING FIXTURE GLOBE

Application filed July 14, 1932. Serial No. 44,319. Term of patent 7 years.

To all whom it may concern:

Be it known that I, MEYER BENJAMIN CHERNIAK, a citizen of the United States, residing at 1802 Longfellow Avenue, in the city of New York, county of the Bronx and State of New York, have invented a new, original, and ornamental Design for a Lighting Fixture Globe, of which the following is a specification, reference being had to the accom-

panying drawing, forming part thereof. The figure is a side view of an ornamental design for a lighting fixture globe showing my new design.

I claim:

The ornamental design for a lighting fixture globe substantially as shown.

MEYER BENJAMIN CHERNIAK.
